UNITED STATES PATENT OFFICE.

JOHN F. O'CONNOR, OF CHICAGO, ILLINOIS, ASSIGNOR TO WILLIAM H. MINER, OF CHAZY, NEW YORK.

SIDE BEARING FOR RAILWAY-CARS.

1,323,903.

Specification of Letters Patent.

Patented Dec. 2, 1919.

Application filed March 1, 1916. Serial No. 81,328.

To all whom it may concern:

Be it known that I, JOHN F. O'CONNOR, a citizen of the United States, residing at the city of Chicago, in the county of Cook and State of Illinois, have invented a certain new and useful Improvement in Side Bearings for Railway-Cars, of which the following is a full, clear, concise, and exact description, reference being had to the accompanying drawings, forming a part of this specification.

My invention relates to improvements in side bearings for railway cars.

The object of my invention is to provide a simple and efficient side bearing.

In the drawings forming a part of this specification, Figure 1 is an end view of my improved side bearing mounted between car bolsters,—only part of the bolsters being shown in the drawing. Fig. 2 is an enlarged plan view of the side bearing. Fig. 3 is a cross section on line 3—3 of Fig. 2. Fig. 4 is a longitudinal vertical section on line 4—4 of Fig. 2.

Referring to the drawings, the numeral 5 indicates a body-bolster of a railway car, (substantially one-half of the same being shown in the drawing) and having attached thereto the bearing plate 6. The numeral 7 indicates a railway car truck-bolster, (substantially one-half of same being shown in the drawing) to which is secured my improved side bearing 8. The side bearing is provided with a roller 9 which is adapted to engage against the bearing plate 6, the said roller being of a general cylindrical shape and provided with the longitudinal perforation 10 for the passage of the axle pin 11. The roller may be made of hard iron or other suitable material. The ends of the axle 11 are received in the perforations 12—12 provided in the upright flanges 13—13 of the cradle 14. The cradle 14 is in two parts which engage each other at substantially the central longitudinal line of the side bearing 15, as indicated in Fig. 3 of the drawings. When in assembled position, the side flanges 13 form between them the recess 16 in which the roller 9 operates, and at each end is provided with a trunnion or extension 17 which is substantially circular in cross section, each half of the cradle being provided with a portion of the trunnion that is substantially semi-circular in cross section. Intermediate

50 its ends the bottom of the cradle is inclined

inwardly and downwardly, as indicated at the numerals 18—18 in Fig. 3, forming a longitudinal crown 19 on the under face of the cradle which engages the top face 20 of the bolster 7, the said crown being substantially 60 in the same plane as the lower face 21 of the cradle's trunnions. The two parts of the cradle may be made, if desired, of malleable iron, though it will be apparent that other suitable material may be used. The 65 cradle is held in proper position or engaged to the bolster 7 by means of the clamping plate or saddle 22 which is provided at either side with the flanges 23—23 and at each end with a stirrup 24 that is curved 70 about the adjacent cradle trunnion. This is clearly illustrated by the dotted lines at 25 in Fig. 3 of the drawings. The saddle 22 may be made of pressed steel or malleable iron or other suitable material, and is fastened to the bolster by the rivets 26 or other similar suitable means. The side bearing is adapted to adjust itself laterally to any changes of the plane of the bearing plate 6 in reference to the plane of the adjacent face of the roller that may occur in actual operation of cars through the lateral oscillation or tilting of the bearing upon the crown of the cradle and the trunnions at the ends of the cradle. 85

I claim:

1. In a side bearing for railway cars adapted to be applied to a bolster, the combination with a cradle having spaced side walls and provided with a crowned bottom, of an anti-friction roller having an axle pin, the latter being supported at its ends in openings provided in said side walls so that the roller rotates about an axis relatively fixed with respect to the cradle, a retaining member arranged to extend around said cradle and adapted to be applied over the cradle and be secured to the bolster, and co-operating means on said member and the cradle arranged to hold the cradle in place 90 and at the same time permit the cradle to adjust itself on its crowned bottom in a direction transverse to the axis of the roller. 95

2. In a side bearing for railway cars adapted to be applied to a bolster, the combination with a roller-carrying member having spaced side walls and provided with a crowned bearing face, of an anti-friction roller rotatably mounted within said member about an axis relatively fixed with re- 100 105 110

spect to said member, the roller being interposed between said side walls, a retaining member of substantially rectangular form extending around said roller-carrying member and adapted to be secured to the bolster, and cooperating means on said retaining member and the roller-carrying member, including projections from the roller-carrying member adjacent its crowned face and on opposite sides of the roller, to hold the roller-carrying member in position while at the same time permitting the latter to rock on its crowned face in a direction transverse to the axis of the roller.

15. 3. In a side bearing for railway cars, a bearing plate, a roller opposed thereto, a cradle in which the roller is mounted, and a clamping plate, the cradle being in two parts, each part being provided at its ends with a half trunnion, the clamping plate passing over the trunnions to hold the two parts of the cradle together.

20. 4. In a side bearing for railway cars, in combination: a bearing plate, an opposed roller, a two-part cradle and a clamping plate, each part of the cradle being provided with a flange forming between them a pocket to receive the roller, each part of the cradle being provided at either end with a member, the said members forming together a trunnion at either end of the cradle, and the clamping plate holding said divided trunnions together.

25. 5. In a side bearing for railway cars, a bearing plate, an opposed roller, a two-part cradle, and a clamping plate, the roller being mounted in the cradle, the cradle being provided with a longitudinal crown to engage a bolster, and the clamping plate holding the two parts of the cradle together and adapted to secure it to a bolster.

30. 6. In a side bearing for railway cars, in combination: a bearing plate, an opposed roller, a two-part cradle, a clamping plate and an axle, the axle extending at its ends from the roller, each part of the cradle being provided with a flange to receive the ends of the axle, the cradle when in assembled position having at either end a trunnion, the clamping plate passing over said trunnions to secure the cradle to a bolster.

35. 7. In a side bearing for railway cars, in combination: a bearing plate, an opposed roller, a two-part cradle, an axle, a clamping plate and a bolster, the axle extending at its ends from the roller, each part of the cradle being provided with a flange to receive an end of the axle, each part of the cradle being provided at its ends with a member, the said members forming trunnions at the ends of the cradle, the lower face of the cradle being longitudinally crowned to engage the bolster, and the clamping plate passing over the trunnions

of the cradle to secure the parts of the 65 cradle together and to engage the same to the bolster.

8. In a side bearing for railway cars, an anti-friction roller, a cradle in which said roller is rotatably supported, said cradle being formed in sections with the division therebetween extending lengthwise of the cradle and at right angles to the axis of the roller, and means for mounting said cradle on a bolster.

70. 9. In a side bearing for railway cars, a roller, an axle extending at its ends from said roller, and a cradle, the cradle being provided with a plurality of sections and having openings for the reception of the 75 ends of the axle, the said cradle being further provided with means for holding the sections thereof together.

75. 10. In a side bearing for railway cars, a roller, a cradle to receive the same, and a clamping plate, the cradle comprising a plurality of sections forming a pocket to receive the roller, and having at its ends a divided trunnion, the clamping plate engaging said trunnion to hold the sections 80 of the cradle together.

85. 11. In a side bearing for railway cars, a roller, a cradle within which the roller is received, and a clamping plate, the cradle being composed of a pair of sections arranged transversely of the roller and having at its ends divided trunnions, the clamping plate passing about said trunnions to hold them together and to secure the 90 cradle to a bolster.

95. 12. In a side bearing for railway cars, a roller and a cradle to receive the same, the said cradle being in two sections and having a longitudinal crown extending along the division point between said sections, the 100 cradle being provided with means for holding the said sections together, the crown being adapted to engage a bolster.

105. 13. In a side bearing for railway cars, a roller, a sectional cradle therefor, the cradle 110 being provided at its ends with divided trunnions and having means for securing said sections together, the said trunnions being adapted to engage a car bolster.

115. 14. In a side bearing for railway cars, in combination: a roller, a cradle to receive the same, and a clamping plate, the cradle being composed of a plurality of sections, said sections being provided at their ends with interengaging members forming a trunnion, the clamping plate passing about said 120 trunnions and permitting the oscillation of the trunnions therein.

125. 15. In a side bearing for railway cars adapted to be applied to a bolster having a flat bearing provided on its upper face, the combination with a roller-carrying member having the bottom thereof ar-

- ranged to bear on said flat bearing of the bolster, said bottom of the roller-carrying member being extended inwardly and downwardly from opposite sides thereof toward 5 the longitudinal center of said roller-carrying member to thereby permit said roller-carrying member to adjust itself on said flat bearing in a plane extending lengthwise of the bolster, of a single anti-friction 10 roller mounted within said roller-carrying member and rotatable about an axis relatively fixed with respect to said roller-carrying member, the axis of said roller extending in a direction lengthwise of the bolster, of a retaining member of rectangular 15 form adapted to be secured to the bolster, said retaining member being arranged to be applied after the roller-carrying member is in position on the bolster and extending around said roller-carrying member, the roller-carrying member having 20 means coöoperating with the retaining member permitting the roller-carrying member to adjust itself on said flat bearing of the bolster, said means also preventing accidental removal of the roller-carrying member when the retaining member is secured to the bolster. 25
16. An anti-friction side bearing comprising a retaining member adapted for attachment to a truck bolster, a rocker having side members, an anti-friction roller rotatively mounted in said side members, said rocker having a crowned bottom with its axis arranged transversely of the axis of 30 said roller, and means providing a flat seat for the crowned bottom of said rocker. 35

In witness that I claim the foregoing I have hereunto subscribed my name this 16th day of February, 1916.

JOHN F. O'CONNOR.
